SHUTTLECOCK

Simon Kornbluth, New York, N. Y.

Application October 25, 1954, Serial No. 32,815

Term of patent 7 years

(Cl. D34—5)

Fig. 1.

Fig. 3.

Fig. 2

Fig. 1 is a top perspective view of a shuttlecock, showing my new design;

Fig. 2 is a side elevational view thereof; and

Fig. 3 is a bottom plan view thereof.

I claim:

The ornamental design for a shuttlecock, as shown.
